UNITED STATES PATENT OFFICE.

GEORGE L. KRAMER, OF LAKEWOOD, OHIO, ASSIGNOR, BY MESNE ASSIGNMENTS, TO THE CLEVELAND INDUSTRIAL DEVELOPMENT COMPANY, OF CLEVELAND, OHIO, A CORPORATION OF OHIO.

PORTRABLE PLANER OR LIKE TOOL.

1,412,209.

Specification of Letters Patent. Patented Apr. 11, 1922.

Application filed February 12, 1921. Serial No. 444,543.

To all whom it may concern:

Be it known that I, GEORGE L. KRAMER, a citizen of the United States, and a resident of Lakewood, county of Cuyahoga, and State of Ohio, have invented a new and useful Improvement in Portable Planers or like Tools, of which the following is a specification, the principle of the invention being herein explained, and the best mode in which 10 I have contemplated applying that principle, so as to distinguish it from other inventions.

The present improvements, relating, as indicated, to portable planers or like tools, have 15 more particular regard to tools of this class intended to be driven by fluid operated turbine engines of the sort shown and described, for example, in U. S. Patent No. 1,283,423, dated October 29, 1918, to T. W. Paxton. A 20 portable planer similarly driven forms the subject matter of my co-pending application filed October 7, 1918, Serial No. 257,254, and the present invention may be regarded in part as an improvement upon such planer, 25 one object being to provide an improved construction of bearings for the spindle of the rotor which constitutes the driving element, and for the lubrication of such bearings. Another object is to provide a sup- 30 porting member for the body of the planer proper, which may be more readily adjusted to vary the inclination of such rotor spindle, and thus of the axis of the rotary cutter carried thereby, with respect to the plane of the 35 surface to be worked.

To the accomplishment of the foregoing and related ends the invention then consists of the means hereinafter fully described and particularly pointed out in the claims, 40 the annexed drawing and the following description setting forth in detail certain mechanism embodying the invention, such disclosed means constituting, however, but one of various mechanical forms in which the 45 principle of the invention may be used.

In said annexed drawing:

Fig. 1 is a plan view of a portable tool, specifically a planer, embodying my present improvements; and Fig. 2 is a central vertical section thereof taken on the plane indicated by the line 2--2, Fig. 1.

Referring to the figures of said drawing, the body of the planer there shown will be seen to comprise two principal elements, a

plate-like member 1 that forms the base of 55 the body, and a top member 2 of general circular form that fits into a circular recess in the upper face of said member 1. Said top member is recessed on its under face so as to provide, in conjunction with a complementary recess in the base member, a chamber in which is rotatably mounted a rotor 3 de- 60 signed to be driven by compressed air or other equivalent pressure fluid, such rotor being, for example, of the general type de- 65 scribed and shown in the patent referred to above. The spindle 4, upon which, at an intermediate point, said rotor is attached, is journaled at its upper end in a ball bearing 5 mounted centrally in top member 2, while 70 another larger ball bearing 6 is mounted between a depending annular flange 7 on the under side of said top member and a hub 8 on said rotor.

The pressure fluid for driving the rotor is 75 received through a supply line (not shown) connected with a suitable hollow handle 10 that is attached at its inner end to a hollow boss 11 on said top member, the opening 12 in which freely communicates with an annular chamber 13 formed in the side wall of the recess in the bottom member 1. A ring 14 is fitted between the two members 1 and 2 so as to close off the interior face of recess 13, save for a series of openings 15 that are 80 drilled or otherwise formed in said ring to allow the air to escape from the annular chamber thus formed in a series of jets that strike against the periphery of the rotor, in order to set the latter in motion. It will be 85 understood that by varying the number of said jet openings 15 the rate of flow of the pressure fluid may be increased or decreased with a corresponding change in the rate of speed of the rotor. It will be observed (see 90 Fig. 2) that the openings 15 lie adjacent the upper side of the peripheral face of the rotor, and that the lower edge of the ring 14 is bevelled or cut away so as to allow the air to escape through openings 16 in bottom member 100 1 from the pockets in the periphery of the latter after such air has done its work.

The handle 10, through which air is supplied to the tool, is provided with a suitable valve, not shown in detail, arranged to be 105 controlled by a lever 20 pivotally mounted on said handle, as will be readily understood. A second handle 21 is bolted or otherwise

suitably attached to the top member 2 opposite said handle 10 so that the operator may grasp the tool with both hands in order to press the same against the work.

Attached to the lower end of rotor spindle 4 is a cutter or knife 22 that has two oppositely disposed laterally projecting blades formed with reversely directed convex cutting edges that lie on opposite sides of said spindle. The specific design of this cutter forms no part of the present invention, being covered by my aforesaid co-pending application, Serial No. 257,254. In order that said knife or cutter may be brought into proper relation with the surface being worked, a supporting member for the body of the tool is provided, consisting of a flat shoe or sole plate 23 formed with a central opening 24 to allow the blades of the cutter 20 to project therethrough as said cutter is rotated. This shoe is pivotally attached at its one end, preferably that adjacent the end of the body to which handle 10 is attached, through the medium of a U-shaped bracket 25 that has its transverse portion riveted to said plate, while its upstanding arms are pivoted on a transverse rod 26 in bottom member 1 of the tool body proper. Attached to the upper face of plate 23 at 30 its opposite end is a vertically disposed screw 27 that has threaded engagement with the interior of a nut 28 that is in turn exteriorly threaded in a suitable aperture in bottom member 1. As a result it will be seen that, upon rotation of said nut in one direction or the other, the adjacent end of the plate 24 will be moved towards or away from said member 1 so as to cause the cutter 22 to project more or less 40 through the opening 24 in said plate, and at the same time vary the angular relation of said plate with respect to the body of the tool, and thus to the axis 4 of the rotor spindle, which likewise constitutes the axis 45 of the cutter. The screw 27 is preferably attached to the plate by means of a transverse pin 29 held in a slotted bracket 30 on said plate, so as to allow for necessary swiveling action as well as longitudinal adjustment of the screw, and thus avoid any binding effect; and in order to retain the screw in adjusted position a spring-pressed plunger 31 suitably housed in member 1 engages with slots 32 formed in the periphery of nut 55 28, as will be readily understood.

The upper face of rotor 3 is cut away between the hub 8 and the periphery of said rotor so as to leave an upstanding flange 35 adjacent the latter, such flange being curved inwardly to bring its inner edge a trifle beyond a correspondingly curved face 36 on the under side of top member 2 that lies without the depending flange 7 on the latter, forming part of the mounting for ball bearing 6; and a series of openings 37 extend

from the channel thus provided to the interior space above such bearing that immediately surrounds the spindle 4. An annular casing 38, suitably attached to the upper face of top member 2, provides a lubricant 70 containing chamber directly over ball bearing 5, and in order to retain the oil or equivalent lubricant in said chamber from flowing too freely downwardly through said bearing 5, a plurality of flat washers 39 are 75 placed in said chamber. The lower of these washers is preferably formed with a central opening as shown in Fig. 2, and the washers are held between two plates 40 and 41 that are movable towards each other so as to expel the oil in said washers, when desired, through an aperture 42 in the lowermost plate. A knob 44 on the upper plate that projects above the housing permits the operator to press said plate downwardly when 80 desired. The oil, after passing through ball bearing 5, will flow under gravity through the lower main bearing 6, and then collect on the upper face of the rotor, as will be evident. The latter of course, when the tool 85 is in operation, travels at a high speed, so that the centrifugal force will cause the oil to flow radially outwardly until the recurved flange 35 is encountered, with the result that the oil, as it flies off against the curved face 90 36, has sufficient momentum to drive it through the openings 37 again into the space above ball bearing 6. In other words, such oil as passes through the bearing 5 is thereafter automatically caused to circulate 95 through ball bearing 6 over and over again. The latter being the principal bearing, danger of overheating is practically eliminated, and the occasional pressing down of knob 45, assuming the oil chamber 38 to have been 100 filled, will keep the bearings of the tool at all times thoroughly lubricated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a tool of the character described, the combination of a chambered body, a bearing in said body, a rotary tool-spindle journaled in said bearing and extending through the chamber in said body, and a member mounted on said spindle and lying in such chamber, said member being formed with an inwardly curved flange disposed to collect lubricant after passing through said bearing, the contiguous wall of such chamber being formed to receive such lubricant from such flange and return same to the other side of said bearing.

2. In a tool of the character described, the

- combination of a body recessed to provide a circular chamber, a rotary tool-spindle axially disposed in such chamber, a bearing in said body for said spindle, and a rotor 5 mounted on said spindle and lying in such chamber, said rotor being formed with an inwardly curved flange disposed to collect lubricant after passing through said bearing, the contiguous wall of such chamber 10 being formed to receive such lubricant from such flange and return same to the other side of said bearing.
3. In a tool of the character described, the combination of a body recessed to provide 15 a circular chamber, a rotary tool-spindle axially disposed in such chamber, spaced bearings in said body for said spindle, said body being formed with radial passages connecting such chamber with the space between said bearings, and a rotor mounted 20 on said spindle below the latter and lying in such chamber, said rotor being formed with an inwardly curved flange disposed to collect lubricant after passing through the adjacent bearing, the contiguous wall of such chamber 25 being formed to receive such lubricant from such flange and return same to the other side of said bearing, through such radial passages.
- lubricant from such flange and return same to the other side of said bearing through such radial passages.
4. In a tool of the character described, 30 the combination of a body comprising a base member formed with a circular chamber, and a top member formed with a circular flange depending into such chamber, spaced bearings in said top member proper and 35 such depending flange, the latter being formed with radial passages between such bearings, means for supplying lubricant to such first bearing, a spindle journaled in said bearings, and a rotor mounted on the 40 lower end of said spindle and lying in such chamber, said rotor being formed with an inwardly curved flange disposed to collect lubricant after passing through the adjacent bearing, the contiguous wall of such chamber 45 being formed to receive such lubricant from such flange and return same to the other side of said bearing, through such radial passages.

Signed by me, this 9 day of February, 50
1921.

GEORGE L. KRAMER.
